DESIGN FOR A SMOKING STAND

Alfred Spitzer, Cambridge, Mass.

Application January 6, 1934, Serial No. 50,332

Term of patent 7 years

To all whom it may concern:

Be it known that I, Alfred Spitzer, a citizen of the United States residing at 202 Sidney Street, Cambridge, in the county of Middlesex, and State of Massachusetts, have invented a new, original, and ornamental Design for Smoking Stands, of which the following is a specification, reference being had to the accompanying drawing, forming part thereof.

The figure is a perspective view of a smoking stand showing my new design.

I claim:

The ornamental design for a smoking stand as shown.

ALFRED SPITZER.
